CONCEALABLE MEMO-PAD WALLET

Filed Nov. 30, 1944

UNITED STATES PATENT OFFICE

2,475,067

CONCEALABLE MEMO-PAD WALLET

John P. Wege, St. Paul, Minn., assignor to
Brown & Bigelow, St. Paul, Minn.

Application November 30, 1944, Serial No. 565,935

1 Claim. (Cl. 150—35)

1.

This invention relates to a concealable memo pad wallet which is designed to support a memo pad in position to be readily concealed when not desired for use. A wallet of this character is usually carried in the user's pocket and may be used for carrying papers, letters, and other items usually carried in the coat pocket of the user of the wallet.

A feature resides in supporting the memo pad on one side of the wallet and in this case the memo pad is supported on an outer wall of the wallet.

It is also a feature to provide a flexible restraining member which holds the support for the memo pad to limit the movement of the same into and out of the concealing pocket formed on the outside of the letter wallet. This restraining means may be made of fabric, leather, or any other suitable material which permits the memo supporting member to be hinged along the upper edge of the pocket so that the memo pad will fold down in operative position on the outside of the main wallet.

The memo supporting member is made rectangular in shape and is provided with a tongue receiving recess or means for receiving and supporting the tongue or back sheet formed on the memo pad which is adapted to support the memo pad to the pad supporting member and removable so that a new pad may be placed on the pad supporting member when the old pad has been used. The pad supporting member may be formed with a short pocket on the back of the same, together with a leather framed opening, which opening is covered by a cellophane window and which opening is provided for a picture.

When the memo pad is not desired for use it may readily be concealed within the pocket provided for the same, which also conceals the pad supporting member, leaving the letter or paper wallet with a neat outer appearance and with the pad and support therefor practically entirely concealed, except for the upper edge of the support within the pocket which encloses and slidably receives the memo pad and its support.

A wallet of this character is desirable because instead of having the memo pad support within the wallet itself the memo pad is supported on the outer wall of the wallet, virtually entirely concealed within a pocket, making it a compact, good looking wallet which is desirable for supporting a memo pad.

A further feature of my concealable memo pad wallet resides in providing a wallet wherein the memo pad is normally concealed so that the body

2.

of the wallet may be used to support letters, papers, or similar articles within the same, readily accessible for reference without disturbing the memo pad which is concealed on the outside of the wallet. Heretofore letter wallets of this character have been made with the memo pad within the side walls of the wallet and every time the wallet was used and it was desired to refer to any of the papers within the same the memo sheets were exposed and might even become soiled or injured, thereby reducing the utility of the same.

These features, together with other details and objects, will be more fully and clearly hereinafter set forth.

In the drawings forming a part of the specifications:

Figure 1 illustrates one form of my letter wallet showing the concealable memo pad means positioned on the outside of the same.

Figure 2 illustrates the wallet with the memo pad withdrawn from the concealing pocket and in position to be used, the dotted lines illustrate the movement of the pad out of the concealing pocket as it is removed longitudinally from the pocket; the arrows indicate the swinging movement of the memo pad after it is withdrawn to position it in place to be used resting against the outside wall of the wallet.

Figure 3 is the section on the line 3—3 of Figure 1 showing the memo pad concealed within the pocket and showing one form of restraining member for the pad supporting member.

Figure 4 is a similar section to Figure 3 on the line 3—3 of Figure 1 showing another form of restraining member for limiting the movement of the pad supporting member as it is withdrawn from the concealing pocket.

Figure 5 is an enlarged section on the line 5—5 of Figure 2.

Letter wallet A is provided with the integral main side walls 10 and 11 which are integrally formed together on the back folded line 12 so that the wallet is compact when these side walls are folded together and secured to each other along their bottom edge and is adapted to receive letters or papers within the same. The wallet A may be formed with pockets (not shown) within the same, as may be desired.

The principal feature of this invention resides in providing a concealable memo pad on one of the outer walls of the wallet or on either or both of the walls so that two memo pads (not shown) may be used if desired. If a second memo pad is desired it would be identical with the one

presently to be described, positioned on the outside of the other side wall of the wallet.

In the drawings I have illustrated the pocket 13 formed on the outside of the wall 11 of the wallet A.

The pocket 13 is secured to the wall 11 in any suitable manner and is adapted to provide a means of concealing a memo pad B.

As a rule the wallet A is made out of leather or similar material. Therefore, the pocket 13 is also made out of leather so as to provide a long-wearing, desirable leather pocket wallet which, owing to the nature of the same, is formed compact and with any suitable design on the outside of the same to decorate the wallet and make it more attractive. I have not illustrated any decoration on the wallet shown in the drawings.

The advantage of my wallet resides in providing a means of concealing the memo pad B within the pocket 13 when it is not desired for use. Thus when the memo pad B is concealed within the pocket 13 the sheets 14 of the memo pad are held compact and protected against wear and soiling or wrinkling so that when the pad is desired for use it may be readily withdrawn from the pocket 13, as illustrated in Figure 2.

I provide a pad supporting member 15 which is made out of leather or similar material and on one face of the member 15 I provide a loop 16 for receiving the tongue 17 to support the memo pad B on the member 15. Member 15 is made comparatively stiff and may be made up of several layers of leather sewed or secured together to form a firm, rigid back support for the memo pad B.

The tongue 17 may be in the form of a stiff or heavy paper sheet attached to the back of the memo pad B and is adapted to form a holding means for securing the memo pad to the supporting member 15.

The supporting member 15 is adapted to be restrained in its movement out of the pocket 13 by the flexible member 18 which is in the form of a band-like member and may be made of cloth or other flexible material or any nature. The member 18 is approximately the same width as the pad supporting member 15. The pad supporting member 15 is slightly narrower than the width of the pocket 13 so that the pad supporting member with the memo pad B will slide freely into and out of the pocket 13 when the outer end of the member 15 is engaged to remove the memo pad B from the pocket 13.

Member 18 is secured at one end at 19 to the top of the member 15 and the other end of the member 18 is secured at 20 in the bottom end of the pocket 13. When the memo pad B is inserted into pocket 13 the flexible member 18 will fold, as illustrated in Figure 3. When the memo pad B is withdrawn from the pocket 13 the member 18 will restrain the withdrawing movement of the pad and permit the pad supporting member 15 to hinge with the pad over the top edge 21 of the pocket 13.

The member 18 may be made in short form, as illustrated in Figure 4, and when in this form one end of the same may be secured at 22 virtually halfway between the top and bottom of the pocket 13.

My concealable memo pad wallet provides a desirable pocket letter piece, having the advantage of concealing the memo pad on the inside surface of an outside wall of the wallet where the memo pad is ready for use at any time without opening the wallet or disturbing any papers contained within the wallet. Furthermore, if in the use of the wallet it is desirable to refer to any of the papers held within the wallet between the side walls 10 and 11 this may be readily done without disturbing the memo pad B concealed in the pocket 13. In this manner I provide a utility pocket wallet of a very desirable nature which can be made very compact, provide a neat appearance and it will conceal papers and letters within the same, or calling cards or any other articles usually carried in the pocket of the user.

A further advantage of my wallet resides in keeping the memo pad in compact, neat form, with the sheets of the pad protected within the pocket 13.

I claim:

A wallet with a concealable memorandum pad including side walls secured together along one of their sides and bottom edges, a flat pocket formed on the outer surface of one of said side walls, a flexible band-like strip of material secured within the bottom portion of said pocket, a pad supporting member, said band-like strip being secured to the upper end of said pad supporting member to limit the movement of said pad supporting member with relation to said pocket, a receiving means secured transversely adjacent the upper end of said pad supporting member adapted to receive the back cover of a pad for attaching said pad to said pad supporting member, whereby said pad together with said pad supporting member may be concealed within said pocket or pulled therefrom and positioned on the outer surface of said pocket in predetermined position.

JOHN P. WEGE.
